COMBINED DESK PEN SUPPORT AND DAILY CALENDAR

James R. Reichow, Minneapolis, Minn., assignor to Brown & Bigelow, St. Paul, Minn., a corporation of Minnesota

Application May 14, 1959, Serial No. 55,907

Term of patent 7 years

(Cl. D74—1)

Fig. 1 is a front perspective view of a combined desk pen support and daily calendar, showing my new design;

Fig. 2 is a front elevational view thereof;

Fig. 3 is a side elevational view taken from the right;

Fig. 4 is a rear elevational view thereof;

Fig. 5 is a side elevational view thereof taken from the left; and

Fig. 6 is a top plan view thereof.

The broken line illustration of the pens in Fig. 1 is for illustrative purposes only.

I claim:

The ornamental design for a combined desk pen support and daily calendar, as shown and described.
